UNITED STATES PATENT OFFICE.

HOMER J. P. HAMPTON, OF JERSEY CITY, NEW JERSEY.

REGISTER.

1,301,691.

Specification of Letters Patent. Patented Apr. 22, 1919.

Application filed April 20, 1912, Serial No. 692,047. Renewed September 8, 1915. Serial No. 49,613.

To all whom it may concern:

Be it known that I, HOMER J. P. HAMPTON, a citizen of the United States, and resident of Jersey City, in the county of Hudson and State of New Jersey, have invented 5 certain new and useful Improvements in Registers, of which the following is a specification.

My invention relates to improvements in registers, and has particular reference to registers commonly called "taximeters" for registering the distance traveled, the time consumed, and the amounts payable for the service.

15 One of the objects of my invention is to provide improved means to permit the step-by-step forward rotation of one or more of the numbering or indicating wheels for a complete rotation, and the return of said 20 wheel to normal at the termination of any complete rotation of said wheel, and likewise the return of said wheel to normal at the termination of any incomplete rotation thereof, whereby such wheel may continue 25 to indicate units, tens, or the like, as required, and will be automatically returned to normal at the termination of each complete rotation, as stated, without unduly winding a spring that restores the wheel 30 to normal.

Further objects of my invention are to cause proper registration of various items, not only of the initial amounts to be charged, but the complete charge for mileage during 35 pay service, the charge for time service, for extras, and the like, when my invention is used as a taximeter.

My invention comprises novel details of improvement and combinations of parts 40 that will be more fully hereinafter set forth and then pointed out in the claims.

Reference is to be had to the accompanying drawings forming part hereof, wherein,

Figure 1 is a side view of a register adapted 45 as a taximeter and embodying my invention, showing the parts in the normal position of "flag up" when a passenger is not using the vehicle, but then capable of registering idle or dead mileage;

Fig. 2 is a partly broken front view looking 50 from the left in Fig. 1;

Fig. 3 is a side view, partly broken, looking 55 at the side opposite that shown in Fig. 1;

Fig. 4 is a plan view of the register, partly 60 broken away;

Fig. 5 is a vertical section, substantially

on the line 5, 5, in Fig. 6, looking in the direction of the arrows, being a view from the rear of the machine;

Fig. 6 is a section substantially on the line 6, 6, in Fig. 5, looking in the direction of the arrows, parts being broken away;

Fig. 7 is a section on the line 7, 7, in Fig. 4 looking in the direction of the arrows;

Fig. 8 is a cross section substantially on the plane of the line 8, in Fig. 7, looking in the direction of the arrow;

Fig. 9 is a detail section on the line 9, 9, in Fig. 8, looking in the direction of the arrows x, x;

Fig. 10 is a section on the line 10, 10, in Fig. 8, looking in the direction of the arrows y, y;

Fig. 11 is a partly broken plan view of the numbering or registering wheels 15, 15^a, 75 15^b and 15^c, and their pawls.

Fig. 12 is a sectional view through the numbering wheels 15, etc.;

Figs. 13, 14, 15 and 16 are sections respectively on the planes of the lines 13, 14, 80 15 and 16 in Fig. 12;

Fig. 17 is a detail view, partly in section, looking at the numbering wheels and their pawls from the left in Fig. 7;

Fig. 18 is a section on the line 18, 18 of 85 Fig. 2;

Fig. 19 is a detail perspective view of part of the extra-charge registering devices;

Similar numerals of reference indicate corresponding parts in the several views. 90

The numeral 1 indicates a suitable frame or casing for the mechanism, in which is suitably journaled a main driving shaft 2, which may be rotated step by step in any suitable manner. For this purpose I have 95 shown said shaft provided with a ratchet 3 engaged by a spring-pressed stop pawl 4, and actuated by a pawl 5 carried by rock arm 6, shown pivoted upon casing 1 at 7, see Fig. 1. Arm 6 may be rocked by any suitable means operated in any wellknown manner from the road wheels of a vehicle or other driving part, as by a flexible shaft to be connected with rock arm 6, as by means of a link 6^a, Fig. 1. In the arrangement 100 illustrated I have provided means for causing shaft 2 to rotate a desired distance, say, for instance, two teeth of the ratchet, for ordinary service, and a greater distance, say three teeth of the ratchet, for extra service. 110 For this purpose I have shown a movable stop 8 (Fig. 1) normally held by spring 9

- in contact with stud 10 on casing 1, and adapted, when in the position shown in Fig. 1, to engage the end 5^a of pawl 5, to release the latter from ratchet 3 on the return stroke of said pawl during each full movement of arm 6, but when an extra fare is to be registered the stop 8 is moved back and held set, as in dotted lines in Fig. 1, so that pawl 5 will continue in engagement with ratchet 3 for an extra tooth, thereby on the forward movement of pawl 5 turning shaft 2 a distance of, say, three teeth. For this purpose shaft 11, to which the flag or signal 12 may be attached in any wellknown manner, is shown provided with a finger 11^a (Fig. 1) which is in such position as not to engage stop 8 when the flag is raised or is in the horizontal or "flag-down" position, (which latter would be the position for recording ordinary fares), but if an extra fare is to be recorded shaft 11 is turned farther to the left in Fig. 1 to cause finger 11^a to engage stop 8 and push the same the proper distance away from pawl 5, as in dotted lines in Fig. 1. A spring 12, bearing against the head 11^b on shaft 11, serves to retain said shaft in set positions, by reason of the flat portions 11^c, 11^a, 11^b, on said head engaging said spring.
- Upon a rod or shaft 14 extending across casing 1 are loosely mounted any desired number of registering wheels or disks 15, 15^a, 15^b, 15^c carrying the desired numerals, as from 1 to 9 and 0 (see Fig. 2), the wheel 15, however, only being provided with, say, three zeros. The wheels 15, 15^a, etc. are to be rotated step by step in the required order to indicate the fares registered or other accounting to be accomplished. If it be assumed that the initial charge is to be, say, thirty cents for a definite distance, as for one-half mile of travel, and that each one-quarter mile thereafter is to be registered, the wheel 15 will normally be set to expose its zero *a*, the wheel 15^a will normally be set to expose its numeral 3, and the wheels 15^b, 15^c will normally be set to expose their zeros (Fig. 2). At the termination of the first quarter mile of travel wheel 15 will be turned to bring its zero *b* in line with the numeral 3; at the termination of the next quarter mile wheel 15 will have been turned to bring its next zero in line with numeral 3, and at the same time wheel 15^a will be turned to bring its numeral 4 in line with the last named zero to register the next coming quarter mile, and so on thereafter for each quarter mile to be registered, but after the first one half mile has been registered wheel 15 will not be advanced any farther, retaining its last zero in the line of reading. These results are accomplished as follows: On the side of each of said wheels is secured a suitable ratchet wheel 16, 16^a, 16^b, 16^c, respectively, having a desired number of teeth, in the example illustrated the teeth being spaced equal to twenty teeth for each such wheel (Figs. 13 to 16). Upon a shaft or rod 17, is hung a rocker 18 carrying pawls 19, 19^a, 19^b, 19^c, to engage ratchets 16, 16^a, 16^b, 16^c respectively. Pawls 19 and 19^a are shown united together, and may operate wheels 15, 15^a jointly at a certain time according to the arrangement of the teeth of their respective ratchet wheels (see Figs. 11 and 17). The pawl 19^c has an extension 19^d located back of pawl 19^b, and extension 19^d has a projection 19^e to ride on toothed disk or rim 16^d formed on or attached to ratchet 16^a (Figs. 11 and 14), and extension 19^d also has a projection 19^f to ride on a toothed disk or rim 16^e formed on or attached to ratchet 16^b (see Figs. 11 and 15). Pawl 19^b has a projection 19^g to ride on disk 16^a. The arrangement is such that at a certain time said projections will enter the teeth of one or both of disks 16^d or 16^e to allow a corresponding pawl to cause the corresponding wheel to rotate a step, according to the arrangement of the recesses of said disks. Said pawls are shown normally pressed forwardly by springs 20, Figs. 6 and 7. Rocker 18 has an extension 18^a shown provided with roller 18^b in engagement with a cam 21 on shaft 2 (Figs. 6, 7, 9 and 10) for rocking said rocker to cause the pawls to rotate the registering wheels when the flag is "down", the rocker 18 being moved out of operative relation to the cam when the flag is "up". Back-stop pawls 22, 22^a, 22^b, 22^c are respectively adapted to engage the ratchets 16, 16^a, 16^b, 16^c, and are shown pivotally supported upon a transverse rod 23. Shaft 11 carries projections 24, 24^a, 24^b, 24^c located beneath pawls 22, 22^a, 22^b, 22^c, respectively, and adapted when the flag is up (Figs. 6, 7 and 8) to raise said pawls from the corresponding ratchets. Shaft 11 also carries projections 25^a, 25^b, 25^c, adapted, when the flag is up, to hold the pawls 19^a, 19^b, 19^c respectively out of engagement with the corresponding ratchets (Figs. 6, 7 and 8). Projections 25^a, 25^b, 25^c are at one side of corresponding projections 24^a, 24^b, 24^c, so that the first named projections will not engage pawls 22^a, 22^b, 22^c. When shaft 11 is turned for flag down for registering, the projections 24, 24^a, 24^b, 24^c allow pawls 22, 22^a, 22^b, 22^c to engage the corresponding ratchets, and projections 25^a, 25^b, 25^c permit pawls 19, 19^a, 19^b, 19^c to engage the corresponding ratchets. Thus, as shaft 2 is rotated step-by-step, when the flag is down, pawls 19, 19^a, 19^b, 19^c will operate to rotate the numbering wheels step by step, and when shaft 11 is turned back and the flag is raised (Fig. 6) the continued rotation of shaft 2 will not operate the numbering wheels. To prevent rocker 18 from operating when the flag is up, I provide means for holding said

rocker out of coaction with cam 21. To this end shaft 11 is provided at the end opposite head 11^b (Fig. 3) with a crank pin 26 connected by the link 27 with a rock arm 28 loose on shaft 17. The end of arm 28 is adapted to engage the projection 18^d of rocker 18 that passes through an opening ^a in casing 1 (Fig. 3), a spring 29 connected with projection 18^d and with casing 1 serving normally to raise the rocker. In Fig. 3 the parts are shown in the positions assumed with flag up and rocker 18 depressed by arm 28, and when shaft 11 is turned in the direction of the arrow (Fig. 3) arm 28 is raised and spring 29 raises rocker 18, thereby permitting the pawls described to have coaction with their corresponding ratchet wheels.

In the arrangement illustrated, with the teeth of the ratchet wheels spaced corresponding to twenty teeth each, I am enabled to place upon the register wheels 15^a, 15^b, 15^c each two sets of numbers from one to nine and zero, each of such sets being upon one-half the periphery of each such wheel. Hence, the disks or rims 16^a, 16^b (Figs. 14 and 15) have two recesses or teeth 16^g, 16^h spaced a distance of ten teeth, and ratchet wheel 16^c has a space 16ⁱ (Fig. 16). The teeth of ratchet 16 (Fig. 13), while spaced equal to twenty teeth, need not be completely around the circumference, since pawl 19 only operates said ratchet a space equal to the last three teeth 16^j (Fig. 13), the remainder of such teeth being in a position to be engaged by pawl 22. The relative arrangement of the ratchet wheels and the recess 16^g, 16^h, 16ⁱ, will be such, with respect to the registering numerals on the corresponding registering wheels 15^a, 15^b, 15^c, that when the zeros of wheels 15, 15^b, and 15^c are in alinement the first tooth 16^j will be engaged by pawl 19 to rotate wheel 15 one step, and numeral 3 of registering wheel 15^a (providing the initial charge is to be thirty cents) will be in alinement with said zeros, and at such time a recess 16^g of ratchet 16^c of numbering wheel 15^a will be in such position that when the numeral 9 of said wheel is exposed in the reading line with the zeros, the extension 19^e of pawl 19^c and the extension 19^g of pawl 19^b will be opposite such recess 16^g until the proper time. The recess 16^h of disk 16^b of ratchet wheel 16^b of numbering wheel 15^b alines with projection 19^f when a numeral 9 of wheel 15^b is in the reading line and at such time the projections 19^f, 19^e, 19^g may fall into the respective recesses 16^h and 16^g and thereupon wheels 15^a, 15^b, 15^c are turned one step together. The recess 16ⁱ of ratchet 16^c of numbering wheel 15^c is in line with a numeral 9 in front, so that when such recess 16ⁱ alines with pawl 19^c the wheel 15^c will not be rotated any farther. With the arrangements described, assuming the initial charge is to be thirty cents and the numbering wheels are in the positions shown in Fig. 2, when the flag is turned down rocker 18 is raised into coaction with cam 21, and as shaft 2 is rotated, either by the road wheel 70 or by the clock mechanism (hereinafter described) pawl 19 on the first rise of rocker 18 will rotate numbering wheel 15 one step by coaction with the first tooth 16^j and on the next rotation of shaft 2 pawl 19 will rotate 75 numbering wheel 15 another step, by coaction with the second tooth 16^j and said pawl falls into the space below the third or last tooth 16^j permitting pawls 19, 19^a to advance to enable pawl 19^a to engage ratchet 80 16^a; upon the next rotation of shaft 2 pawl 19 will not operate wheel 15 any more, (until reset to flag up position) and pawl 19^a on the next rise of rocker 18 will rotate wheel 15^a one step (being an advance charge for the 85 next quarter mile) and so on, wheel 15^a being rotated until ninety cents is registered, at which time a recess 16^g will be in alinement with projections 19^e and 19^g. If the charge now runs to one dollar on the next rotation 90 of shaft 2 the projection 19^g will enter recess 16^g thus permitting pawl 19^a to engage ratchet 16^a, but projection 19^e will be held back by projection 19^f bearing upon the surface of disk 16^b, then upon the next rise of 95 rocker 18 pawl 19^a and pawl 19^b will rotate the respective ratchet 16^a, 16^b turning the corresponding numbering wheels 15^a, 15^b, thus registering one dollar. Registration according to the foregoing is continued until 100 \$9.90 are registered and thereupon a recess 16^g will be in the position last before mentioned and a recess 16^h will have been brought into alinement with projection 19^f, and on the next upward movement of rocker 105 18 the projections 19^e and 19^g will both enter such recess 16^g and the projection 19^f will enter recess 16^h permitting pawls 19^a, 19^b and 19^c to engage their respective ratchets and 110 rotate their respective wheels, thereupon turning wheels 15^a, 15^b, 15^c jointly one step to register \$10. The step by step registration of the wheels will thus occur continuously until space 16ⁱ of ratchet 16^c is brought 115 into alinement with pawl 19^c, whereupon wheel 15^c will not rotate any more, whereupon \$99.90 will have been registered. This being the limit of registration shown in the drawings with four registering wheels, all 120 the wheels may be restored to initial charge. Of course, it will be understood that as many numbering wheels as desired and with their corresponding pawls and parts may be installed. The arrangement set forth is advantageous in that it enables in a simple manner 125 the restoration of the numbering wheels to zero or normal position at any time the flag is turned up. I have illustrated means for such purpose and in order that each of the numbering wheels that may have been oper- 130

ated on a trip will return to zero or normal, at the termination of the trip when the flag is restored or turned up, irrespective of the extent to which such wheels may have been rotated on a trip, and in order also not to unduly wind the springs which cause the restoration of such wheels, I provide the following arrangements, and since the wheels 15 and 15^c are restored by corresponding devices, and the wheels 15^a, 15^b are restored by corresponding devices, a description of one set of each such devices will suffice. Referring first to means for restoring the registering wheels 15^a and 15^b to normal or zero, the arrangements are as follows: The ratchet wheels 16^a, 16^b, are secured to the corresponding numbering wheels 15^a, 15^b, which ratchet and numbering wheels are loose on shaft 14, but are operatively connected with said shaft by spring 30 for restoring the numbering wheels to normal (see Figs. 7, 12 and 15). Spring 30 is connected at one end with shaft 14 and at the other end with a disk 16^k loose on shaft 14. Disk 16^k carries a lever 31 pivotally supported thereon and the end 31^a of said lever is adapted to engage a projection 32 on the corresponding ratchet wheel, whereby when said ratchet wheel is rotated in the direction of the arrow in Fig. 7, projection 32 by engaging lever 31, will cause disk 16^k to be rotated and the spring wound. The arm 31^b of lever 31 is adapted to engage a stud 33 upon the casing when the numbering wheel is approaching the termination of one rotation. The projection 32 is adapted to engage a stop dog 34, as shown in Fig. 7. Dog 34 is pivotally supported upon a rod 35 and held in normal position by spring 36. When ratchet 16^a has been caused to make nearly a complete revolution, carrying the corresponding numbering wheel around with it, and disk 16^k has been correspondingly rotated by engagement of projection 32 with arm 31^a, and projection 32 is approaching dog 34, or engaging the same, arm 31^b will engage stop 33 and at the completion of the stroke of pawl 19^a, lever 31 will have been tilted to release its arm 31^a from projection 32, whereupon spring 30 will cause disk 16^k to return to normal, and projection 32 will pass under dog 34. This enables spring 30 to be wound at least a complete revolution, but prevents overwinding of the spring. Should a numbering wheel, however, be stopped at any other point in its rotation, as by reason of the trip terminating and registering on the numbering wheel any corresponding numeral, then when shaft 11 is turned to show flag up, and the pawls are released from the ratchets, the numbering wheels 15^a, 15^b and their ratchets that have been operated will be returned to normal or zero, by their corresponding springs 30, since at such time the arm 31^b of a lever 31 will remain in engagement with its projection 32.

of the corresponding ratchet wheel, and thereby by reason of the tension of spring 30, the parts will be restored to normal and the projection 32 of a ratchet will come to rest against the end of the corresponding dog 34. By arranging the parts described for any of the numbering wheels desired, it will be apparent that such numbering wheels will be restored to zero by the mere act of turning shaft 11 for flag up.

The numbering wheel 15 need not be provided with disk 16^k and lever 31, but its spring 30^a (Fig. 12) may be connected directly to the numbering wheel 15, and to the shaft, as by being connected with spring barrel 30^b that is secured to shaft 14, and the projection 32^a of ratchet 16 (Figs. 2 and 13) will engage stop 34^a to retain wheel 15 against the tension of its spring to normally expose zero ^a. This arrangement is adopted because registering wheel 15 is not caused to make a complete rotation.

The numbering wheel registering the highest number, such as wheel 15^c, also need not be provided with disk 16^k and lever 31, since such wheel is not intended to make more than one rotation, and in the example illustrated does not make more than one-half rotation. For this purpose spring 30^c (Figs. 12 and 16) is connected with numbering wheel 15^c and with shaft 14 as by being connected with spring barrel 30^d secured to shaft 14. Ratchet 16^c is shown provided with projection 32^b to engage stop 34^b (Figs. 2 and 4), located in such position as to normally retain the zero of wheel 16^c in the reading line (Fig. 2). When wheels 15 and 15^c have been rotated any distance for registering, their return rotation at such time is prevented by the corresponding dog 22 and 22^c, but when shaft 11 is turned for flag up and said dogs release their ratchets their corresponding springs will restore wheels 15 and 15^c to normal, the projections 32, 32^b then engaging the corresponding stops 34^a and 34^b. By the arrangement set forth it will be understood that all of the registering wheels, while advanced step by step for registering, are maintained under spring tension to restore them to their normal positions, and that after registering has occurred with flag down, and the trip or engagement is ended, and the flag is to be turned up, such corresponding rotation of shaft 11 will, by reason of its projections 24, 24^a, etc., raising the stop dogs 22, 22^a, etc., from the ratchets, and the projections 25, 25^a, etc., moving pawls 19^a, etc., back from the ratchets (Fig. 7), permit the springs of any of the registering wheels that have been advanced to cause such registering wheels to return to normal, and be stopped at normal by engagement of their corresponding projections 32 with the stop 34, etc., so that each time that the flag is turned down, the registering wheels will be

in position to start registering in the manner described with the advance or initial charge already registered.

- In order that cam 21 may depress rocker 18 through the action of the road wheel when registering for mileage, as well as to enable registering according to time elapsed when the taxicab is not traveling but is under hire, I provide means to operate rocker 18 and pawls 19^a, etc., under either of such conditions, and to stop such actions when the flag is up, and also to throw into action means for recording of mileage made by the taxicab when the flag is up, as on a return trip from an engagement or when fares are not being registered. To this end I secure a ratchet 36 (Figs. 7 and 8) upon shaft 2, and also mount loosely on said shaft a ratchet wheel 37 to which is secured a gear 38 (Figs. 5, 6 and 8), which gear is adapted to be driven by a gear 39 of a clock train 40 (Fig. 3). Cam 21 carries a pawl 36^a to engage ratchet 36, and also carries a pawl 37^a to engage ratchet 37 (Figs. 5, 6, 7, 8 and 10), which pawls are shown carried by an extension 21^a of said cam. Pawl 36^a has a finger 36^b to be engaged by a cam 41 slideable along shaft 2 (Figs. 5 and 8) and connected with said cam is a cam 41^a to engage finger 37^b connected with pawl 37^a (Figs. 5, 6 and 8). In the arrangement shown in Fig. 8, shaft 2 has an enlarged portion 2^a, having a bore receiving a rod 42 provided with a pin 43 passing through slots in shaft 2 and connected with cams 41, 41^a which are mounted slidably on enlarged portion 2^a of shaft 2 (Figs. 8 and 10), whereby as rod 42 is moved to the right or left said cams will be correspondingly moved. Rod 42 also carries a finger 44 (Figs. 5, 6 and 8) which is adapted, in the position shown in Fig. 5, when the flag is up, to engage a tripper 45 (Fig. 6) of a counter or register 46 of any well known construction, whereby each time shaft 2 is rotated by the road wheel (when the flag is up) the registry wheels of register 46 will be correspondingly operated to register mileage. To slide rod 42 end wise as required, I have shown the outer end of said rod provided with a grooved collar 47 receiving the yoke 48 on a rock-arm 49 pivoted upon casing 1, as at 50. The upper end of arm 49 is shown movably connected by a pin-and-slot connection with a bell-crank lever 51, the upper arm of which engages the forked or slotted end 52^a of rock arm 52 pivotally supported at 53 on the casing (Figs. 3 and 5). The relative arrangement of the parts is such that when the flag is up (Fig. 5) rod 42 will have been pushed inwardly, because crank pin 26 will then be depressed and will have depressed arm 28, rocker 18, and the right hand end of arm 52 (Fig. 3), thereby tilting lever 51 upwardly, causing arm 49 to push rod 42 in-

wardly and thereby cams 41 and 41^a are pushed into engagement with the corresponding fingers 36^b and 37^b and hold their corresponding pawls 36^a, 37^a out of engagement with ratchets 36, 37, (preventing operation of cam 21), and finger 44 will have been brought into coactive relation with tripper 45, whereby rocker 18, pawls 19^a etc., and wheels 15, 15^a, etc. will not be operated either by the road wheel or the clock train, 70 but the register 46 will be operated to record mileage because of the rotation of shaft 2 and plunger 44, which will be such mileage as is not charged for. When shaft 11 is turned with flag down, crank pin 26 will rise, 80 lifting arm 28 from extension 18^a, permitting the rise of rocker 18 and setting the pawls 19^a, 19^b, 19^c and 22, 22^a, 22^b, 22^c in positions for operating the numbering wheels 15, 15^a, 15^b, 15^c, and withdrawing finger 44 85 from alinement with tripper 45, because the forked end of arm 52 then descending tilts lever 51 to cause arm 49 to pull rod 42 outwardly, thereby also shifting cams 41 and 41^a from alinement with fingers 36^b, 37^b, 90 thus enabling the pawls 36^a, 37^a to coact with the ratchets 36, 37. The rotation of shaft 2 by the road wheel will now, through the medium of ratchet 36 acting upon pawl 36^a, cause rotation of cam 21 to operate rocker 95 18 to actuate the registering wheels 15, etc., without affecting register 46. Should the taxicab come to rest with the flag down, the clock-train operating gear 38, will, by such gear, cause ratchet 37 to rotate, which, by 100 engagement with pawl 37^a, will rotate cam 21 to operate rocker 18. As mileage is usually counted at greater speed than time charges, it will be understood that there will be no interference by the action of the 105 road wheel in rotating shaft 2, to operate cam 21, and the clock train operating said cam through the mechanism described. In other words, the devices having the greatest speed for rotating cam 21 at any given time, 110 will operate said cam.

Since cam 21 is rotated continuously by shaft 2 of the clock mechanism when registering is to be effected, and since at the termination of any given trip such cam might 115 stop at a position not its normal position, that is to say, with roller 18^b bearing upon the wide part of the cam and not resting in the depressed part 21^b (Fig. 9), the next user of the cab would be charged for mileage 120 not used by him, since as soon as roller 18^b dropped from the high part 21^a of the cam into the depressed part 21^b of the cam (Fig. 9) the pawls 19^a, etc., would register. To overcome this objection, and to cause cam 125 21 always to be restored to its normal position with roller 18^b normally resting in the depressed part 21^b of the cam when the flag is turned down to start a trip under hire, I provide the following arrangement, which is 130

in many respects similar to the arrangement described with respect to the spring and the tripping device illustrated in Figs. 14 and 15. At one side of cam 21 is a disk A loose on shaft 2 and a spring B is secured at one end to said disk and at the other end to spring barrel C that is secured to casing 1. Disk A carries a lever D normally pressed by a spring E into engagement with a projection 21^a (Figs. 8 and 9) at one side of the high part 21^b of the cam, whereby when said cam is rotated in the direction of the arrow in Fig. 9 disk A will be correspondingly rotated and spring B will be wound. A stop pin F on disk A engages lever D when the parts are in the positions shown in Fig. 9. The arm D' of lever D is adapted to engage a stud G on the casing (Figs. 6 and 9) to trip lever D from projection 21^a of the cam when the cam approaches its normal position to prevent overwinding of the spring B, although when the fares are being registered the cam will continue to rotate indefinitely, disk A being tripped as described each time the cam makes one rotation. When, however, the flag is turned up, and the pressure of roller 18^b against cam 21 is relieved by the depression of rocker 18, and the pawls 36^a, 37^a are then released from the ratchets 36, 37, (by the sliding of cams 41, 41^a to the left in Fig. 8 as before described), the tension of spring B through disk A and arm D against projection 21^a of the cam operating in the reverse direction to the arrow in Fig. 9, will rotate cam 21 in a reverse direction to its normal direction of operation, and the cam will be stopped by the check dog H engaging projection 21^a, at which time roller 18^b of rocker 18 will be in position to fall into the depression 21^b of cam 21 when the flag is next turned down, whereupon cam 21 will then begin to act upon rocker 18, at which time the registering wheels will have been returned to zero so that each passenger will be charged only from the normal positions of the cam 21 and not from any advanced position left from some preceding trip. The check dog H, Fig. 7, is shown pivoted upon the casing at I and held under spring tension by spring J, and thereby projection 21^a, when rotating in the direction of the arrow in Fig. 9, may slide freely past dog H.

In order to register permanently mileage, such as quarter miles (when fares are being charged) I provide a suitable register 60 of any well known character. For this purpose I utilize finger 44 to engage a rock arm 61 (Fig. 6) pivoted at 62 and pivotally connected at 63 with arm 64, of register 60, the spring 65 acting normally to draw the parts, as in Fig. 6, whereby when the flag is turned down and shaft 11 is thus turned to permit pawls 19^a, etc., 22, 22^a, etc., to coact with the ratchets of the registering wheels

15, etc., finger 44 will through the rocking arm 49, have been shifted by rod 42 from alinement with tripper 45 into alinement with arm 61, and the latter will cause arm 64 to rock to operate register 60, each time shaft 2 is rotated.

In order to register each time that the flag is turned down, to thereby indicate the number of initial charges, such as each thirty cents for the first half mile charged, shaft 11 is provided with a projection or cam 68 (Figs. 2, 4 and 5, 7 and 8) adapted to operate arm 69 shown pivotally supported at 70, and pivotally connected with rock arm 71 (Fig. 4) of a register 72, the arrangement shown being such that when the flag is up (Fig. 7) cam 68 will be free from arm 69 and the latter will be depressed by spring 69^a to likewise depress arm 71, and when shaft 11 is turned for flag down, cam 68 will be raised and will engage and raise arm 69, thereby raising arm 71 and causing the proper wheel of register 72 to register. Such turning of shaft 11 thereby registers each initial charge for flag down, or each time the flag is depressed, and on the return rotation of shaft 11, to the position of flag up, arm 69 will be depressed ready for another operation of register 72.

In order to register each charge for fractions of a mile, such as ten cents for each quarter mile after the initial charge (such as thirty cents for the first quarter mile) with flag down, I provide a register 73 which may be supported beneath register 72 and operated each time pawl 19^a is operated. For this purpose the arm 74 of register 73 (Figs. 7 and 11) is pivotally connected with an arm 75, shown hung upon a rod 76 carried by casing 1, a spring 77 connected with arm 75 tending normally to raise the parts. The bent end 75^a of arm 75 lies over a projection 19^x (Figs. 6 and 11) of pawl 19 when shaft 11 is set for flag up, and pawl 19^a is in mesh with ratchet 16^a, whereby each time rocker 18 then rises to register fares, projections 19^x will engage projection 75^a and operate register 73 to indicate each such quarter mile or ten cent charge. When shaft 11 is turned back for flag up and pawls 19^a are withdrawn from their respective ratchets, projection 19^x will be drawn from beneath projection 75^a and register 73 will not operate. A stop 78 (Fig. 6) engages arm 75 to resist the upward pull thereon of spring 77.

In order to register extra charges made while the taxicab is in service or under employ, and also to register the totals of such extra charges for permanent record, I provide the following means: Upon shaft 17 are loosely mounted numbering or registering wheels 80, 81, which may be arranged similarly to registering wheels 15^b and 15^c respectively, having corresponding numerals 130

as before described. The wheel 80 has a ratchet 82 and wheel 81 has a ratchet 83 operated respectively by pawls 84, 85, pivotally carried upon rocker 86, supported by bracket 87 on frame 1. Upon the side of ratchet wheel 80 is a notched disk 88, the two notches 88^a being equally spaced (as on disk 16^a) and a pawl 85^a connected with pawl 85 (Fig. 19) is adapted to ride upon disk 88 and to enter its notches 88^a. When pawl 85^a rides on disk 88 pawl 85 will be held out of engagement with ratchet 83, but pawl 84 being movable independently of pawls 85 and 85^a is always adapted to coact with ratchet 82. Springs 89, 89^a, coacting with pawls 84, 85 and with rocker 86, (Fig. 19) hold said pawls in operative relation to ratchets 82, 83 and disk 88. Pawls 84 and 85 are provided with projections 90 (Fig. 6) adapted, when rocker 86 is depressed, to engage the bottom of said rocker and maintain the pawls out of contact with ratchets 82, 83. The arrangement is such that when rocker 86 rises, turning on the pivot 91, the pawls 84, 85 may engage their respective ratchets, and when rocker 86 descends to the normal position (Fig. 6) projections 90 hold pawls 84, 85 out of engagement with their ratchets permitting reverse rotation of the latter. Rocker 86 is to be raised and lowered, to actuate wheels 80 and 81, and for this purpose I have shown a projection or cam 92 on shaft 93 carried by casing 1 and bracket 87 (Fig. 6) and having a suitable head 94 (Figs. 1, 2 and 5) which may be rotated whenever it is desired to register an extra fare. Registering wheel 80 and its parts may be made in accordance with the construction shown in Fig. 15, having a stop or projection 95, and lever 96 to coact therewith (Fig. 2), the stud 97 serving to trip said lever to release the tension of the spring of wheel 80 to allow the corresponding disk carrying lever 96 to return as described with respect to Fig. 15. The stop dog 98 (Figs. 2, 4 and 18) coacts with stop 95 to cause the zero of registering wheel 80 to come to the reading line when the flag is raised. A pawl 99 (Figs. 1, 2, 5 and 18) for each ratchet 82, 83, is mounted upon shaft 76 (Fig. 18) and adapted to engage corresponding ratchets 82, 83, being normally pressed down by spring 100. Shaft 11 is provided with projections 101 (Figs. 4, 5 and 18) to engage the extensions 99^a of pawls 99, said projections being in such position that when shaft 11 is turned to position of flag up, projections 101, acting upon the projections 99^a, will raise pawls 99 from the ratchets 82, 83, and when shaft 11 is turned flag down, projections 101 will permit pawls 99 to engage their corresponding ratchets to prevent return rotation of numbering wheels 80, 81, as they are being operated forwardly. The numbering wheel 81 and its ratchet 83 are provided with a spring arrangement similar to that shown in Fig. 16, the pin 83^a (Fig. 18) being adapted to engage stop 102 to permit wheel 81 to retain its zero in the reading line with the flag up. In order to register the totals of the numbering wheels 80, 81, I provide a suitable registering device 103 of any well-known construction (Figs. 1, 2 and 6) the operating arm 104 of which is connected by link 105 with projection 92, whereby when the latter is rocked, arm 104 will be rocked to cause operation of the wheels of register 103. Thus, each time projection 92 is raised to cause rocker 86 to operate its pawls to actuate registering wheels 80 or 81, arm 104 will be rocked to register as a permanent total of such operations of wheels 80, 81, regardless of the fact that such wheels 80, 81 are restored to normal or zero position each time the flag is raised.

Changes may be made in the construction and arrangements of parts set forth, within the scope of the appended claims, without departing from the spirit of my invention.

Having now described my invention what I claim is:—

1. A register comprising a numbering wheel, means to operate said wheel, means to retain the wheel in a normal position, a spring, a disk separate from the numbering wheel and connected with said spring, a movable member and a coacting stop on said disk and numbering wheel, and means to release said member from said stop to permit the disk to be rotated reversely by said spring. 95
2. A register comprising a numbering wheel, means to rotate said wheel step by step, means to check rotation of said wheel, means to retain said wheel in a normal position, a spring, a disk separate from the numbering wheel and connected with said spring, a movable member and a coacting stop on said disk and numbering wheel, means to release said member from said stop to permit the disk to be rotated by said spring, and means to release the numbering wheel to permit the spring to return the numbering wheel to normal. 105
3. A register comprising a numbering wheel, a ratchet wheel connected therewith, a check pawl to coact with the ratchet wheel, means to rotate said wheel step by step, a stop connected with said wheel, a disk operative separately from the numbering wheel, a spring connected with said disk to rotate reversely to the step by step operation of the numbering wheel, a member movably connected with the disk to coact with said stop, and means to release said member from said stop to permit reverse rotation of said disk. 120
4. A register comprising a numbering wheel, a ratchet wheel connected therewith, 130

a check pawl to coact with the ratchet wheel,
means to rotate said wheel step by step, a
stop connected with said wheel, a check-stop
5 to co-act with said stop, a disk operative sep-
arately from the numbering wheel, a spring
connected with said disk to rotate reversely
to the step by step operation of the number-
ing wheel, a member movably connected
with the disk to coact with said stop, means
10 to release said member from said stop to
permit reverse rotation of said disk, and

means to release the pawl from the ratchet
wheel to permit the spring to rotate the
numbering wheel in a direction reverse to its
step by step rotation.

15

Signed at New York city, in the county of
New York, and State of New York, this 2d
day of April A. D. 1912.

HOMER J. P. HAMPTON.
